GOBLET

Robert S. Raymer, 14 Adams Road,
Marblehead, Mass. 01945

Filed Sept. 28, 1972, Ser. No. 292,980

Term of patent 14 years

Int. Cl. D7—01

U.S. Cl. D7—13

FIG. 1 is a front elevational view of a goblet, showing my new design,

FIG. 2 is a section on line 2—2 of FIG. 1,

FIG. 3 is a top plan view, and

FIG. 4 is a bottom plan view.

The rear and side elevation are identical with the front elevation.

I claim:

The ornamental design for a goblet, as shown and described.
